UNITED STATES PATENT OFFICE.

JAMES BOGAN BELK, OF CHARLOTTESVILLE, VIRGINIA

DISPLAY-CABINET

1,253,125.

Specification of Letters Patent

Patented Jan. 8, 1918.

Application filed June 28, 1916. Serial No. 106,494

To all whom it may concern:

Be it known that I, JAMES BOGAN BELK, a citizen of the United States, residing at Charlottesville, in the county of Albemarle and State of Virginia, have invented new and useful Improvements in Display-Cabinets, of which the following is a specification.

This invention relates to improvements in display cases or cabinets of the type generally used by clothiers.

The invention aims to provide a garment support or rack associated with the case or cabinet to be slid in and out of the latter, and when arranged exteriorly thereof capable of being rotated in either direction to fully display the stock, or to bring any particular garment within convenient reach of the salesman.

20 In carrying out the invention I provide means for holding the clothes rack positioned within the casing or disposed exteriorly thereof, thus preventing casual rearrangement of the rack under all circumstances.

It is also my purpose to provide a construction whereby the garment support or rack can be either suspended from the top, or supported from the floor of the case, or both, and in either instance mounted for sliding and rotatable adjustment.

With these and other objects in view, the nature and advantages of the invention will be better understood as the following description is read in connection with the accompanying drawings, the invention residing in the construction, combination and arrangement of parts as claimed.

In the drawings forming part of this specification like numerals of reference indicate similar parts in the several views and wherein:—

Figure 1 is a front elevation partly in section.

45 Fig. 2 is a top plan view partly in section.

Fig. 3 is a perspective view of the clothes rack support.

Fig. 4 is an enlarged detail sectional view showing one position of the locking element. Fig. 5 is a fragmentary sectional view

Fig. 5 is a fragmentary sectional view showing another position of the locking element.

Fig. 6 is an enlarged detail sectional view showing the manner of supporting the rack from the top of the case.

Referring more particularly to the draw

ings in detail A indicates the display case or cabinet which may be of any suitable construction, B the doors for controlling access to the cabinet, and C the clothes rack or support.

The latter preferably consists of an elongated rectangular frame 10, the parallel side walls of which are longitudinally slotted as at 11, providing tracks for the grooved wheels 12, which latter are arranged upon the opposite extremities of rollers 14 and preferably form part of the latter. There are two such rollers 14 which are suitably spaced, and supported upon the rollers is a platform 15, from the under side of which depends apertured lugs 16 through which the rollers 14 are extended. The platform 15 is provided with a central opening in which one end of a tubular casing 17 is threaded, the tubular casing receiving the standard 18 that supports, at its upper end, the rack frame 20 which may be of any suitable design and proportions. Depending from the platform 15 in alignment with the opening therein is a socket 21 having an upwardly curved bottom 22 upon which rests the rounded bearing 23 on the lower end of the standard 18, which construction permits the rack 20 together with the standard 18 to be easily rotated in either direction as the occasion may require. The frame 10 is arranged within the space between the bottom D of the case and the false bottom E, while the tubular member 17 is disposed within the case A through an elongated slot 24 in the false bottom E. The component parts of the clothes support are capable of movement as a unit longitudinally of the frame 10, and can be easily moved out of the casing 10 or returned to normal position within the casing with the least effort.

For the purpose of holding the rack against casual derangement in any of its adjusted positions I preferably employ a 100 spring pressed locking element 25 arranged within a transverse bore 26 in the platform 15. The locking element is provided with a head 27 against which one end of an extensible spring 28 is adapted to bear, the spring being arranged within the bore 26 and having its opposite end bearing against the end wall of the bore to normally hold the head 27 of the locking element projected through an opening 29 in the tubular member 17, and seated within a depression 30 in the standard 110 18. The bore 26 opens at one edge of the

platform 15, while the stem 31 of the locking element projects through said bore and by reason of its engagement with the adjacent side wall of the frame 10, the locking element is held in the depression 30 of the standard and prevents casual rotation of the latter. To prevent movement of the rack longitudinally of the base 10, I provide the lower walls of the slots 11 adjacent the opposite extremities thereof with depressions 32, which are alternately engaged by the rollers 14 to hold the rack as a unit at either end of the casing 10 in its adjusted position.

15 In practice the rack can be easily moved longitudinally of the frame 10 to position the rack exteriorly of the case A, in which position of parts the stem 32 of the locking element is brought into alignment with the 20 opening 33 in the adjacent side wall of the frame 10. The rack can then be easily rotated, by rotating the standard 18, the curved wall of the depression 30 co-operating with the rounded or curved surface of 25 the head of the locking element to force the latter out of the depression 30, which movement of the locking element is permitted by the opening 33 which receives the stem 32 when the locking element is adjusted to a released 30 position. Manifestly the stem 32 of the locking element is held within the opening 33 while the standard is being rotated, and in which position the stem 32 functions to prevent movement of the rack as a unit 35 longitudinally of the frame 10. When the standard has been rotated to bring the depression 30 into alignment with the bore 26, the locking element assumes its normal position, subsequent to which the rack as a unit 40 can be moved within the case A. It is of course to be understood that one or more racks 20 may be mounted upon the standard 18 if desired, and that the component parts of the device may vary in design without departing 45 from the spirit of the invention.

If desired the rack proper indicated at 20 may be suspended from the top of the case or cabinet A as clearly illustrated in Fig. 1. In this instance a partition F is disposed immediately beneath the top of the cabinet in spaced relation thereto, and a frame 34 identically of the same construction as the frame 10 hereinabove described and its associated parts, is interposed between the partition F and the top of the cabinet. Arranged upon the platform 35 is a flange 36 suitably grooved to receive ball bearings 37, which are held in the groove by means of a flanged collar 38 keyed upon the standard 39, which latter enters the frame through a hollow boss 40 forming part of the flange 36 and depending through a suitable opening in the platform 35. Rising from the platform 35 are apertured lugs 41 constituting bearings 45 for the rollers 42 which are mounted

upon the frame 34 in the same manner as hereinabove described with reference to the rollers 14. Manifestly the rack 20 is supported immediately adjacent the top of the cabinet or case A, and can be spaced any desirable distance therefrom by increasing or decreasing the length of the standard 39. Obviously the rack at the top of the cabinet can be moved outwardly thereof, and subsequently rotated to display all of the stock, or to bring any particular garment in convenient reach of the salesman. The standard 39 is held against casual rotation by means of a spring pressed locking element 43 which permanently bears against the 80 standard 39. One side of the frame 34 is provided with a suitable opening 44 to allow the locking element to yield sufficiently to permit the standard to be easily rotated, but the standard is provided with a depression 85 45 which receives the locking element 43, whereby the rack is locked against casual rotation within the cabinet. A single cabinet can be provided with racks supported from the base, or from the top, or from both 90 of these points as shown in Fig. 1, depending upon what particular use the cabinet is to be put, that is to say upon the style of garment the cabinet is to contain.

While it is believed that from the foregoing description the nature and advantages of the invention will be readily apparent, I desire to have it understood that what is herein shown is merely illustrative of one embodiment of the invention to which I do 95 not limit myself, and that such changes may be resorted to when desired as fall within the scope of what is claimed.

What is claimed is:—

1. A display apparatus of the character 105 described embodying an elongated frame, a platform mounted between the side walls of the frame for movement longitudinally of the latter, a standard rising from the platform and mounted for rotation, a garment 110 supporting rack carried by the standard, said platform having a transverse bore, a spring pressed locking pin fitted within the bore and engaging said standard to normally prevent rotation thereof, said side wall of 115 the frame having an opening adjacent one end adapted to register with said bore when the platform is moved to the limit of its adjustment in one direction, to permit a retraction of said locking pin, and rotation of 120 the standard.

2. A display apparatus embodying an elongated frame having longitudinally disposed slots in the opposed side walls thereof, a platform arranged to slide between said 125 walls, rollers supporting said platform, grooved wheels on the opposite ends of said rollers and operating within said slots, the lower wall of each slot being formed with a depression adjacent each end thereof for 130

the reception of the wheels for limiting the movement of the platform in either direction, a standard rising from the platform and capable of rotation, a spring pressed locking pin carried by the platform and normally engaging said standard to prevent rotation thereof, one wall of said frame hav-

ing an opening to permit a retraction of said pin upon limit of the movement of said platform in one direction, and a garment supporting rack carried by said standard.

In testimony whereof I affix my signature.

JAMES BOGAN BELK.
